Attorney

UNITED STATES PATENT OFFICE.

JOHN H. GILBERT, OF PLANT CITY, FLORIDA.

LOCK.

1,240,838.

Specification of Letters Patent. Patented Sept. 25, 1917.

Application filed July 2, 1917. Serial No. 178,221.

To all whom it may concern:

Be it known that I, JOHN H. GILBERT, a citizen of the United States, and resident of Plant City, in the county of Hillsborough 5 and State of Florida, have invented certain new and useful Improvements in Locks, of which the following is a specification.

This invention relates to new and useful improvements in locks, and the primary 10 object of the invention is to provide a lock of this character which is especially adapted for use on warehouse, stable doors or the like, and the device includes a sliding shackle fastener provided with means for 15 locking the same, and a slidable keeper normally adapted to positively engage the shackle when the same is in locked position, and movable out of operative position, so as to expedite the quick releasing of the 20 lock.

Another object of the invention is to provide a device of this character, which is easily and simply constructed, inexpensive to manufacture, and one which will be very 25 efficient in operation.

With these and numerous other objects in view, my invention consists of the novel features of construction, combination and arrangement of parts which will be herein 30 referred to and more particularly pointed out in the specification and claims.

In the accompanying drawings.

Figure 1 is a perspective view of the lock; and

Fig. 2 is a vertical section through the same.

In describing my invention I shall refer to the drawings in which similar reference characters designate corresponding parts 40 throughout the several views.

The numeral 1 designates a main body portion, which is tubular, being provided with a longitudinally extending slot 2, in the lower end 3 thereof. The slot 2 extends 45 along the body portion to a point approximately half the length thereof, and adapted to be positioned within said body portion is a slidable shackle 4, which has one portion 5 therein which is the longest leg 50 of said shackle slidably mounted through the main body portion 1, with its lower end bent laterally and provided with a knob 6 on the extremity thereof. This laterally bent portion of the leg 5 of the shackle is 55 adapted to engage the longitudinally extending slot 2, when the hasp is released, as

clearly shown in Fig. 1 of the drawings. The shorter leg 7 of the shackle 4 which forms the locking portion of the same projects laterally therefrom. The shackle 4 60 is adapted to be held in locked position by means of a pivoted locking lever 8, which is semicylindrical, having one end thereof pivotally connected with the body portion 1, and the free end of said lever projects below 65 the lower end 3 of said body portion. The lower free end of said lever is provided with a notch portion 9 therein, adapted for engagement with the laterally bent portion of the leg 5 of the shackle, when the shackle is in 70 locked position, as clearly shown in Fig. 2 of the drawings. The locking lever 8 is only in operative position when the shackle is locked, and then the lever owing to its semi-cylindrical shape is adapted to be swung 75 down parallel with and partly surrounding the tubular main body portion 1. A fastening member 10 may be secured to the body portion preferably mounted on the lever 8, so that the lock may be held in position on 80 the warehouse door or the like.

Disposed substantially parallel with the main body portion 1, is a supplemental tubular body portion 11 provided with open ends, and supported adjacent the main body portion by a pair of projecting loops 12 that are carried by the said main body portion. This supplemental tubular body portion 11 forms a casing, and has its upper end lying 85 flush with the upper end of the main body portion 1. The supplemental body portion 11 has formed therein a longitudinally extending slot 13 having its upper end extending laterally as shown at 14 for a purpose to be hereinafter more fully described. 90

Slidably mounted within the supplemental body portion 11 is a keeper 15 which is operable by a projecting stud 16 that extends through the slot in the supplemental body portion 11. When not in operation, the slidable keeper is normally positioned so that its upper end is disposed within the tubular body portion, but when the same is in operative position, as clearly shown in Fig. 2 of the drawings, the upper end of 105 said keeper projects from the body portion, so as to receive the leg 7 of the shackle 4.

In operation when the various parts of the lock are disposed as clearly shown in Fig. 1 of the drawings, it will be apparent 110 that the slidable keeper 15 has its upper end projecting above the upper end of the sup-

plemental body portion 11, and consequently the main body portion 1. The keeper is held in this position, by the projecting operating stud thereof being arranged in the 5 bent portion 14 of the slot in said supplemental body portion, this holding the keeper in said position and prevent any movement thereof. When it is desired to lock the shackle, the knob 6 is grasped and pulled down 10 out the slot 2 and the main body portion 1, until the same is positioned beneath the lower end of said body portion, whereupon the swinging locking lever 8 will engage the laterally bent end of the leg 5 of the shackle 15 in the notch in the free end thereof. This sliding movement of the shackle will bring the locking leg 7 thereof down into the projecting portion of the keeper 15. This will securely hold the lock in operative position 20 and the projecting portion of the keeper forms a strengthening reinforcement for the shackle.

To release the parts of the lock, the lever 8 is swung outwardly, and the knob grasped 25 and moved upwardly into the slot 2, whereupon the opposite end of the shackle will be raised out of engagement with the keeper, and to expedite the quick release of the object engaged, the keeper is dropped down 30 into the supplemental body portion 11, by moving the stud 16 out of the slot 14, and down along the slot 13, so as to withdraw the projecting end of said keeper.

This type of lock is especially adapted for 35 use on warehouse doors, stable doors, or the like. The slideable keeper having a projecting end is adapted to strengthen the shackle, and also expedites the quick release of the lock from operative position. This forms 40 a keyless lock, and one that is easily and simply operated in a very efficient manner.

From the above description taken in connection with the accompanying drawings, it is thought that a clear and comprehensive 45 understanding of the construction, operation, and advantages of my invention may be had, and while I have shown and described the device as embodying a specific structure, I desire that it be understood that

such changes may be made in said structure 50 as do not depart from the spirit and scope of the invention as claimed.

Having fully described my invention, what I claim as new, and desire to secure by Letters Patent, is:—

1. A lock of the class described including a body portion, a shackle slidably mounted therein, a pivoted lever adapted for engagement with the shackle to lock the same, and a keeper for said shackle adjustable in the 60 direction of movement of the same.

2. A lock of the class described including a main body portion, a shackle slidably mounted therein and projecting from one end of the same, a supplemental body portion disposed parallel with the main body portion, and a keeper slidably mounted therein and movable beyond the end of the main body portion for positive engagement with the shackle.

3. A lock of the class described including a main body portion, a shackle slidably mounted therein and projecting from one end of said body portion, a supplemental body portion disposed substantially parallel 75 with the main body portion and having its end lying flush with the end thereof, a keeper slidably mounted in the supplemental body portion and adapted to project therefrom, and means for locking said keeper in projected position.

4. A lock of the class described including a tubular body portion, a shackle slidably mounted therethrough, a keeper adapted to be coöperatively engaged with one end of the shackle, the other end of said shackle being bent laterally and having a knob formed on the extremity thereof, a hollow semicylindrical lever pivotally mounted on the tubular body portion, and the free end of said lever having a notch therein adapted for engagement with the bent end portion of the shackle when the lever is disposed parallel with the body to hold the shackle in locked position.

In testimony whereof, I affix my signature hereto.

JOHN H. GILBERT.
